UNITED STATES PATENT OFFICE

163,529

TOY ORGAN

Finn H. Magnus, Essex Fells, and Emil J. Ens,
Newark, N. J., assignors to Magnus Harmonica
Corporation, Newark, N. J., a corporation of
New Jersey

Application August 8, 1950, Serial No. 11,668

Term of patent 14 years

(Cl. D56—1)

To all whom it may concern:

Be it known that we, Finn H. Magnus and Emil J. Ens, citizens of the United States, residing at 13 Wooton Road, Essex Fells, State of New Jersey and 240 Sunset Avenue, Newark, State of New Jersey, respectively, have invented a new, original, and ornamental Design for a Toy Organ, of which the following is a specification, reference being had to the accompanying drawing, forming a part hereof.

Fig. 1 is a perspective view of a toy organ showing our new design;

Fig. 2 is a rear elevational view; and

Fig. 3 is an end elevational view thereof.

We claim:

The ornamental design for a toy organ, substantially as shown.

FINN H. MAGNUS.
EMIL J. ENS.
